UNITED STATES PATENT OFFICE.

ESKIL H. JOSEPHSON, OF LONG ISLAND CITY, NEW YORK.

TALKING-MACHINE REPEATER AND STOP.

Application filed December 23, 1921. Serial No. 524,389.

To all whom it may concern:

Be it known that I, ESKIL H. JOSEPHSON, a citizen of the United States, residing at Long Island City, in the county of Queens 5 and State of New York, have invented certain new and useful Improvements in Talking-Machine Repeaters and Stops, of which the following is a specification.

This invention relates to repeating devices 10 for phonographs and the like and the primary object of the invention is the construction of a novel and an improved device capable of being used in connection with various types of phonographs wherein the 15 selection may be played and repeated without stopping the turn table.

Another object of the invention is the provision of a repeating device for phonographs and the like cooperatively arranged 20 with the tone arm, including means adapted to be engaged by the outer periphery of the turn table, whereby the said tone arm is moved to its initial playing position.

Another important object of the invention 25 is the provision of a repeating attachment for phonographs which may be set to play continuously or a predetermined number of times, including an adjusting mechanism so that the device is capable of use with various 30 size records as well as permitting repetition of certain portions of a record as desired.

A further object of the invention resides 35 in the construction of a repeating attachment for phonographs, including a novel and improved gear mechanism operable by a friction wheel from the turn table permitting the tone arm to be moved to its initial playing position automatically.

A still further object of the invention is 40 to provide a repeating attachment of the above character which will be durable and efficient in use, one that will be simple and easy to manufacture and one which can be placed upon the market and incorporated 45 with a phonograph at a reasonable cost.

With these and other objects in view the invention consists in the novel construction, arrangement and formation of parts as will be hereinafter more fully described, 50 claimed, and illustrated in the accompanying drawings, in which drawings,

Figure 1 is a plan view showing the device in its relation with a tone arm of a phonograph,

55 Figure 2 is a view taken on the line 2—2 of Figure 1,

Figure 3 is a view taken on the line 3—3 of Figure 2, showing the friction wheel and trip mechanism,

Figure 4 is a further view taken on the 60 line 4—4 of Figure 2.

Referring to the drawings in detail, wherein similar reference characters designate corresponding parts throughout the several views 5 designates the turn table 65 and 6 the tone arm having the usual reproducer 7 attached thereto, the same being common to various types of phonographs and to which the invention is adapted to be connected.

The repeating device proper is secured in any well known manner on the casing of the phonograph and comprises a substantially rectangular housing 8, the top 9 of which may be formed integral or separable 75 with the hollow upstanding casing 10, as shown in Figure 2 of the drawing. The casing 10 is preferably provided with a curved top 11 and the same rotatable and rockable receives the reproducer engaging 80 L-shaped rod 12 which embodies the short leg 37 and the long leg 13, the outer end of which engages the bracket 14 on the reproducer 7. Attached to the casing 10 and adjacent the top thereof, I have provided an adjustable bracket 15 formed with a collar 16 adjustable by means of a screw 85 17 to various positions, so that different size records may be played or such portions of a record, as desired may be repeated during 90 the continuous operation of the turn table. The bracket 15 is provided with a vertical arm 18 which engages the long leg of the L-shaped rod 12 when the rod is in its initial playing position.

95 It will be observed that the leg 13 of the L-shaped rod 12 is inclined downwardly with respect to the horizontal when the same is in its normal or initial position and that the short leg 37 is inclined with respect 100 to the vertical for a purpose which will presently appear.

Pivottally mounted within the housing 8 I have provided a gearing mechanism for bringing about the returning of the tone to 105 its initial playing position. The gearing is mounted within a suitable frame including top and bottom plates 19 and 20, which are connected together by posts 21 at their respective corners. The top plate 19 is provided with a laterally extending finger 22 110 operable in a slot 23 of the housing 8 where-

by the entire gear mechanism and frame may be rocked on a pivot post 24 which is rotatably carried by a bracket 25 attached to the casing 8.

5 A friction wheel 26 is disposed between the plates 19 and 20 and is rotatable with a post 27 which is mounted in suitable bearings carried by the plates. The friction wheel 26 extends through a slot 28 in the 10 front of the housing 8, so that when the gear casing is moved by the finger piece 22, for instance, to the dotted line position (see Figure 3), the friction wheel 26 will engage the outer periphery of the turn table and rotate counter clockwise, consequently rotating the meshed gears 29 and 30 whereby the meshed gears 31 and 32 on the posts 33 and 20 34 respectively will be put into operation. It is to be noted that the gear 32 is secured to the post 24 and that the post is rotated thereby.

Thus it can be seen that while the gear frame is pivotally mounted on the post 24, the post is adapted to rotate and consequently operates the cam 35 counter clockwise which is connected to the upper end thereof. This cam 35 overlies the top plate 19 and is provided with a pocket 36 therein for receiving the lower end of the short leg 37 30 of the L-shaped rod 12, so that when the gear mechanism is put into operation by the friction wheel engaging the turn table the cam will rotate moving the lower end of the short leg 37 about the pivot post 24 35 rocking the L-shaped rod on the curved top 11 of the casing 10, which will lift the leg 13 and move the same laterally with the reproducer back to its initial playing position. It is to be understood that when the reproducer reaches its initial playing position that the continued rotation of the cam 35 40 will further rock the L-shaped rod and gradually lower the leg 13 until the needle of the reproducer engages the record at the point where it is desired to be repeated.

Adjacent to the hollow casing 10 there is provided an adjustable stop member 40 embodying a vertical leg and a substantially horizontally disposed leg. The vertical leg 50 is rotatably carried by the top wall 9 of the housing 8 and by a bracket 41 secured to the casing 10. The substantially horizontally disposed leg of the stop member 40 is provided with an upwardly bent end 42 55 for engaging the leg 13 of the L-shaped rod 12 so as to form a stop for the same, as set forth above. The lower end of the vertically disposed leg of the stop 40 carries a pair of friction washers 43 between which the curved arm 44 is grasped, the arm lying adjacent to the inner wall of the housing 8 60 (see Figure 3). The opposite end 45 of the curved arm 44 is adapted to engage the outer end 46 of the curved lock and trip arm 47 which is pivotally mounted as at 48 to

the housing 8. The opposite end of the arm 47 is provided with a depending foot 49, which engages a notch 50 in the outer end of one arm 50' of a T-shaped bar 51. The T-shaped bar 51 is pivotally mounted on the plate 19 by means of a pin 53 and the leg or stem thereof is connected with the trip and lock arm 47 by a coil spring 52. In other words one end of the spring 52 is connected to the arm 47, thus being indirectly connected to the housing 8 and the opposite end of the spring is attached to the T-shaped bar 51 and consequently indirectly attached to the gear frame. The T-shaped bar 51 is provided with an arm 54 extending oppositely from the arm 50' and this arm engages the cam surface of the cam plate 35. Now it is to be noted at this point that when the foot 49 engages the notch 50 on the arms 50' of the T-shaped bar that movement of the arm 50' and T-shaped bar is limited causing a pivot point at 49 and 50 and the spring 52 acting on the leg or stem of the bar will cause force to be applied to the gear frame at the pivot point 53 of the T-shaped bar 51 thus turning 51 about 49 and 50 which will tend to rock the frame on the post 24 and thus normally hold the frame in and the friction wheel 26 out of engagement with the turntable.

In order to bring about the repeating of the selection and the stopping of the turn table when the record or selection has been played the desired number of times a controller disk 55 is provided which is secured to the lower end of a pivot pin or post 56' 100 rotatably supported by the top wall 9 of the housing 8. This disk is adjusted by the means of a finger piece 57^a which is secured to the pin or post 56' and is adapted to operate over the upper surface of the said wall 9. A plurality of teeth 56 is formed on one portion of the periphery of the disk 55 and the disk may be set according to various designations on the top 9, so that the record may be played continuously or once, twice, three or four times which of course depends upon the number of teeth that may be provided.

A bell crank shaped brake arm 57 is provided and pivoted at its angle to the lower surface of the top plate 9 of the housing 8 and one end of the brake arm is provided with a brake shoe 59' which is adapted to be normally moved into engagement with the periphery of the turn table of the phonograph for bringing about the stopping thereof by a leaf spring 57^a, which is also carried by the housing 8. The opposite end of the brake arm 57 is provided with a foot for engaging the curved portion of the periphery of the controller disk 55. Now it is to be noted that the controller disk 55 at the periphery thereof is provided with a notch 60' and it is obvious that when the foot on

the brake arm rides into the notch that the 5
brake arm is free to rock on its pivot under
influence of the spring 57^a and that the
brake shoe 59' will be brought into frictional
5 contact with the turn table.

When the controller disk 55 is rotated in
a counter clockwise direction so as to position
10 all of the teeth 56 out of the path of the
leg 37 of the L-shaped rod 12, it will be
recognized that the device will be set to play
continuously and that the foot of the brake
15 arm will be in engagement with the curved
edge of the disk and be held out of engagement
with the turn table. When the disk is
set to repeat the record one or more times
20 the disk is positioned so that one or more of
the teeth 56 will be successively engaged by
the leg 37 of the L-shaped rod 12 according
to the number of times that the record is to
25 be played. It is to be understood of course
that the teeth of the controller disk 55 are
adapted to be engaged by the leg 37 of the
rod 12 and that when the leg 37 is rotated
30 about the pivot 24 by the cam 35, the leg
will engage between the teeth 56 and move
the disk 55 one tooth at a time upon each ro-
tation of the cam 35. Now it can be seen
35 that when the leg 37 moves the last tooth
56 over, the foot on the brake arm 57 will
ride off of the curved surface of the disk 55
40 into the notch 60' of the disk thereby allow-
ing the brake arm to be moved to its opera-
tive braking position.

A coil spring 60 is provided for aiding in
45 the return of the tone arm to its normal
position and this spring will function so as
to normally tend to rotate the L-shaped rod
12 toward the arm 18 of the stop 15. As
shown this spring 60 is coiled about the leg
50 37 of the L-shaped rod 12 and attached at
its upper end to the rod and at its upper
end to a stud 61 carried by the extension 62
of the top wall 9 of the housing 8. This ex-
55 tension extends inwardly toward the center
of the casing 10.

It is to be noted however that when the
cam 35 rocks the rod that the arm 13 will
have a tendency to normally swing toward
the bracket 15. In instances when the turn
50 table is electrically operated, the movement
of the brake arm 57 may also control a
switch not shown to close a circuit connected
up with the operating mechanism of the
phonograph.

55 In operation of the improved repeating
attachment the stops 40 and 15 are adjusted
to the size of the selection being played
after which the needle is placed in the outer
groove of the record and the tone arm mov-
60 ing inwardly will rotate the L-shaped rod
12 in the pocket 36 until the end of the
selection is played at which time the leg 13 of
the L-shaped rod 12 will engage the stop and
trip 40 which will rock the same in the

bracket 41. This rocking movement of the 65
trip and stop 40 will rock the arcuate arm
44 which in turn will rock the trip and
catch arm 47 moving the foot 49 thereof
from out of engagement with the arm 50'
of the T-shaped bar 51. This will now per-
mit the gear frame to be moved outwardly
70 of the housing 8 toward the turn table under
the influence of the spring 52 and the
friction wheel 26 will be held in contact
with the turn table by the said spring. 75

The rotation of the friction wheel 26 op-
erates the meshed gears 29 and 30 which in
turn operates the gear 32 on the vertical
shaft 24 and consequently rotates the cam
35 mounted on the upper end of the shaft 80
24. The rotation of the cam 35 which car-
ries the lower end of the leg 37 of the re-
producer engaging rod 12 consequently ef-
fects the movement thereof when rotated.
The rotation of the cam 35 rocks the 85
L-shaped rod 12 so as to cause the raising of
the leg 13 and the canted position of the
leg 13 and the stop spring 60 will move the
arm back against the stop 15 to its initial
position. The continued rotation of the 90
cam 35 will again change the angle of the
reproducer arm 12 and permit the lowering
of the reproducer until the needle engages in
the first sound groove. As soon as the cam
35 is operated through the gears, the same 95
will at once act on the curved end of the arm
54 of the T-shaped bar 51 rocking the same
on its pivot 53 and moving the arm 50'
thereof under the foot 49 of the trip arm
47 consequently again latching and holding 100
the T-shaped bar. When the high point of
the cam 35 engages the curved end of the
arm 54 of the T-shaped bar 51 the repro-
ducer will be in its lowered position and
when the curved end of the arm 54 rides off 105
of the high point of the cam a pivot will be
produced at the foot 49 and notch 50 and
the spring 52 pulls on the T-shaped bar
causing force to be applied to the gear frame
110 or casing at 53 thereby turning the T-shaped
bar 51 at the point 49 and 50 thus rocking
the gear frame on the pivot 24 moving the
friction wheel 26 from out of engagement
with the turn table. The turn table will of
course again start rotating and the rod 12 115
will be moved inwardly with the reproducer
starting the operation of the repeating at-
tachment over again.

Assuming that the regulating or con-
troller disk 55 is set to play the selection 120
once, and the end of the leg 37 of the L-
shaped rod 12 engages the innermost tooth
56 causing the rotation of the disk 55 one
tooth, this foot of the brake arm to ride into
the notch 60'. The brake arm 57 will be 125
released and the turn table will be brought to
a stop. The rotation of the cam 35 will of
course also engage the curved end of the arm

54 of the T-shaped rod 51, so that the catch will be moved to its initial locking position as heretofore described.

5 By moving the point or indicator 57^a to its various designated positions on the casing the disk dish 55 can be set, as the same cooperates therewith and the selection may be repeated a number of times or if so desired can be played continuously, as heretofore 10 stated.

15 In the accompanying drawings I have illustrated my invention embodied in one form by way of example and which construction has been found to answer a satisfactory degree the results to be obtained. It would be manifest, however, that other forms or embodiment may be adopted and that the construction may be variously changed and modified by the skilled mechanic without 20 departing from the spirit of the invention. Further it should be understood that the invention is not limited to any particular form of construction in the parts, except in so far as such limitations are specified in the 25 subject matter being claimed.

Having thus described my invention, what I claim as new, and desire to secure by United States Letters Patent is:

1. The combination with a phonograph 30 including a tone arm and a turn table, of a repeating attachment for the phonograph including a housing disposed adjacent to the turn table including an upstanding hollow casing, a disk rotatably mounted in the housing at the axial center of and below the hollow casing having an eccentrically disposed pocket therein, an L-shaped reproducer engaging rod rotatably and rockably mounted at the upper end of the hollow casing having 35 the lower end thereof rotatably mounted in the pocket, and means for rotating the disk by the turn table after a record has been played, whereby the lower end of the rod will travel a circular path to cause the raising and tilting of the outer end of the rod to permit the returning of the tone arm to its initial playing position.

2. The combination with a phonograph 50 including a tone arm and a turn table, of a repeating attachment therefor including a hollow casing, a disk rotatably mounted in the housing at the axial center of and below the hollow casing having an eccentrically disposed pocket therein, an L-shaped reproducing rod rotatably and rockably mounted at the upper end of the hollow casing having the lower end thereof rotatably mounted in the pocket, the disk having a 55 cam surface, a T-shaped bar pivoted at the point of connection of the arms thereof to the housing and having one arm engaging the cam surface, a pivoted latch for engaging the T-shaped arm, a spring connecting the latch and the T-shaped bar together,

60 a gear frame rockably mounted on the pivot 65 of the disk supporting the T-shaped bar, means including a friction wheel carried by the rocking frame for rotating the disk, and a trip arm disposed in the path of the tone arm for moving the latch out of engagement 70 with the T-shaped bar, as and for the purpose specified.

3. The combination with a phonograph including a tone arm and a turn table, of a repeating attachment therefor including a 75 hollow casing disposed adjacent to the turn table, an upstanding hollow casing carried by the housing, a disk rotatably mounted in the housing at the axial center of and below the hollow casing having an eccentrically 80 disposed pocket therein, an L-shaped reproducer engaging rod pivotally and rockably mounted at the upper end of the hollow casing having the lower inner end thereof rotatably mounted in the pocket, a gear frame 85 rockably mounted on the pivot of the disk, means for rotating the disk including a friction wheel carried by the frame, the disk having a cam surface, a T-shaped bar pivoted at its angle to the frame engaging with the cam surface of the disk, a latch lever 90 adapted to engage the T-shaped bar when the same is in one position, a spring connecting the T-shaped bar with the latch lever normally urging the same outwardly 95 when the T-shaped bar is out of engagement with the latch lever and for urging the frame inwardly when the T-shaped bar is in engagement with the latch lever and when the arm of the T-shaped lever rides off of the 100 high point of the cam surface of disk, a controller disk rotatably mounted in the housing adjacent to the first mentioned disk provided with a plurality of teeth on one 105 side thereof adapted to be engaged by the reproducer engaging rod, a brake arm, normally urged toward the periphery of the turn table the brake arm being adapted to engage the circular edge of the controller disk when the same is in one position for holding the brake arm out of engagement 110 with the turn table, the movement of the reproducer engaging arm by the cam being adapted to rotate the controller disk in a step by step movement when the teeth thereof are disposed in the path of said rod, said controller disk having a notch in the periphery thereof for permitting the operation 115 of the brake arm when the notch aligns with the brake arm, as and for the purpose specified.

120 In testimony whereof I affix my signature in presence of two witnesses.
